US0D1083851S

(12) **United States Design Patent** (10) **Patent No.:** **US D1,083,851 S**
(45) **Date of Patent:** ** *Jul. 15, 2025

(54) **CIRCUIT BOARD**

(71) Applicant: **The Noco Company**, Glenwillow, OH (US)

(72) Inventors: **James P. McBride**, Phoenix, AZ (US); **Matthew Michael Bosway**, Gilbert, AZ (US)

(73) Assignee: **The Noco Company**, Glenwillow, OH (US)

(*) Notice: This patent is subject to a terminal disclaimer.

(**) Term: **15 Years**

(21) Appl. No.: **29/901,553**

(22) Filed: **Sep. 1, 2023**

(57)

CLAIM

The ornamental design for a circuit board, as shown and described.

DESCRIPTION

The sole FIGURE is a perspective view of a circuit board, showing our new design.

(Continued)

The broken lines shown in the drawings depict environmental structure or portions of the article that form no part of the claimed design.

All surfaces not shown form no part of the claimed design.
